UNITED STATES PATENT OFFICE

SAMUEL E. PAYSON, OF BROCKTON, MASSACHUSETTS, ASSIGNOR TO HAMILTON-WADE COMPANY, OF BROCKTON, MASSACHUSETTS, A CORPORATION OF MASSACHUSETTS

DESIGN FOR A WELT STRIP

Application filed October 24, 1930. Serial No. 37,366. Term of patent 14 years.

To all whom it may concern:

Be it known that I, SAMUEL E. PAYSON, a citizen of the United States, residing at Brockton, in the county of Plymouth and Commonwealth of Massachusetts, have invented a new, original, and ornamental Design for Welt Strips, of which the following is a specification, reference being had to the accompanying drawing, forming a part thereof.

In the drawing, the figure is a view in perspective of a welt strip ornamented with the design of my invention, and in which certain portions are shaded to indicate a contrast of color.

I claim:

The ornamental design for a welt strip as shown and described.

SAMUEL E. PAYSON.
